FLEXIBLE COASTING SLED

Albert J. Scholtes, Baltimore, Md.

Application June 20, 1934, Serial No. 731,504

9 Claims. (Cl. 280—22)

The present invention relates to sleds and similar vehicles using runners for gliding over ice, snow and the like, and has for an object to provide an improved construction for guiding the sled which embodies means for flexing the runners throughout their entire lengths.

Another object is to provide the sled with guiding handles, for the hands or feet depending upon the sitting or lying position of the rider, 10 which are relatively close together and set into the sides of the sled and behind a bumper to protect the hands and feet of the rider, and to provide a guiding mechanism controlled by the handles which requires but little energy expenditure for operation so that the steering mechanism of the sled is responsive under slight pressure on the handles.

A further object of the invention is to provide a sled of this type with a novel construction of runner the surface contacting edge of which is bifurcated or divided so as to present a pair of spaced apart cutting edges with the edges offset to opposite sides of the medial plane of the runner so that the runner will automatically seek to stabilize itself by supporting the runner with both of the cutting edges on the surface. Furthermore, this type of runner admits of easy sharpening of the cutting edges and at the same time provides an interposed channel or groove in the bottom of the runner within which ice and snow may rise to form virtually a trackway for better holding the runner from side slipping.

Another feature of the present invention is to embody the above enumerated improvements in a construction which follows the general conventional lines of sleds of this character.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of a flexible coasting sled embodying the features of the present invention.

Figure 2 is a bottom plan view of the same.

Figure 3 is a fragmentary enlarged longitudinal section taken vertically and centrally on the line 3—3 of Figure 1 through the forward end portion of the sled.

Figure 4 is a transverse section taken through the handle bar of the sled on the line 4—4 of Figure 1.

Figure 5 is a similar view taken through the

rear end portion of the sled on the line 5—5 of Figure 2.

Figure 6 is a bottom plan view of the sled showing the runners flexed to change the direction of movement of the sled, and

Figure 7 is a detail fragmentary view taken substantially on the line 7—7 of Figure 2 showing on an enlarged scale the bracket connection between the rear end of one runner and the sled body.

Referring now to the drawings the invention is shown by way of illustration as applied to a flexible coasting sled wherein a top platform or body part 10 is of the usual slat construction with the slats secured in their relative positions upon cross pieces 11, 12 and 13. The cross pieces 11, 12 and 13 may extend beyond the sides of the platform 10 and are recessed, as shown particularly in Figure 5, for accommodating side rails or hand hold 14 in the usual manner. At the forward ends of the side rails 14 are provided a pair of inwardly arched or bowed arms 15 which extend in a general forward direction and are connected at their forward ends by rivets 16 or the like to the opposite end portions of a bumper 17 or front rail 17. The front rail 17 is preferably curved or of arcuate form with the ends extending backwardly, and the ends of the rails 17 preferably project beyond the rivets 16 and have apertures 18 therein for the reception of a draft rope or the like by means of which the sled may be drawn forward when it is not desired to guide or steer the sled. The bumper or bar 17 is also pivotally connected, by the rivets 16 or the like, to the forward ends of a pair of runners 19 which are curved upwardly to meet the bar 17. Shifting of the bar or bumper 17 toward one side of the sled flexes the forward ends of the runners 19 in the direction in which the bar 17 is shifted.

To shift the bar 17 the same is provided with a forward lever 20 pivoted at 21, by means of a pin, bolt or the like as shown to the intermediate portion of the bar 17. The forward lever 20 extends rearwardly and centrally of the sled and at its intermediate portion is mounted on a pivot 22 which is carried by a slat projection 23 of the platform 10. This projecting portion 23 of the platform is preferably reinforced by top and bottom plates 24 which are riveted or otherwise suitably secured against the upper and lower sides of the projection and which are suitably apertured for receiving the pivot pin 22 therethrough. The lever 20 extends rearwardly beneath the projection 23 and secured across the lever 20 rearwardly of the pivot 22 is a handle 25

bar 25 which may be of sheet metal of the desired width and thickness and which is arched downwardly at its intermediate portion, as shown in Figure 4, to engage the lever 20. The opposite end portions of the handle bar 25 are offset upwardly into substantially the plane of the platform 10 and extends outwardly at opposite ends toward the sides of the sled and carries handles 26 which are secured upon the upper sides of the ends of the handle bar. These handles 26 are of any suitable shape or configuration to conveniently receive the hands in grasping the handle bar to secure a firm hold on the same.

These handles 26 are also adapted at times to receive the feet thereagainst as when the rider is in a sitting posture on the platform 10. The handles 26 are undercut or recessed at their inner lower sides as shown at 27 to provide guideways for the inwardly arched or curved arms 15. The arms 15 thus hold the handle bar from being twisted or bent downwardly at either end, and the recesses 27 are of sufficient depth to admit of the free swinging of the handle bar on its pivot 22, through the lever 20 into various positions for controlling the steering of the sled. The handle bar 25 is rigidly fixed to the lever 20 by two or more rivets 28, as shown, so that when the handle bar is swung about its pivot the lever 20 maintains its angular relation with respect to the handle bar so that the lever 29 itself is swung on the pivot 22 and shifts the bumper 17 either to the right or left. The runners 19 extend rearwardly in normal parallel relation beneath the platform 10 near the opposite sides thereof and preferably in line beneath the side rails 14. Each runner 19 is connected at spaced points by brackets 29, 30 and 31 either directly or indirectly to the body portion of the sled. The cross piece 11 beneath the forward portion of the sled is directly connected to the forward brackets 29 such as by bolts 32, rivets or the like which extend through suitably slotted openings formed in the brackets 29 to admit of the necessary movement of the runners 19 when flexed.

The intermediate brackets 30 are riveted or otherwise secured to the runner 29 and are interconnected across the under side of the sled body by a bar 33 which slidably fits against the under side of the intermediate cross piece 12, as shown in Figure 5, so that the brackets 30 with their connecting bar 33 and the intermediate portions of the runners may freely shift from side to side beneath the sled body. The rear brackets 31 are secured directly to the rear cross piece 13 by bolts 34 or the like, the brackets 31 being suitably slotted to admit of the turning of the brackets with the runners when the latter are fixed, as shown in Figure 6. Both of the pairs of brackets 29 and 31 are pivoted to the body part or frame 10 of the sled as shown respectively by the pivots 32' and 34'. As the flexing or bowing of the runners 19 between the pivots 32' and 34' requires a shortening of the distance between said pivots, the brackets 29 have slots 32'' for the pivots 32', the slots 32'' extending lengthwise of the runners 19 to admit shifting of the brackets 29 as the runners 19 are flexed. There is thus a floating or differential movement of the brackets 29 during the flexing of the runners so that the latter may assume continuous curves or arcs of different radii without binding or undue strain on any of the pivots or brackets during the steering movements.

The other suitable slot and bolt or pin arrange-

ments may be resorted to for holding the runners and their brackets to the body of the sled and admitting of the necessary flexing of the runners throughout their entire lengths. For the purpose of flexing the intermediate portions of the runners in a direction opposite to the flexing of the forward ends of the runners, a rear flexing lever 35 is used. The lever 35 is secured by a pivot 36 to the intermediate portion of the cross bar 33 and the intermediate part of the rear lever 35 is mounted on a pivot 37 which projects downwardly from the platform 10 and may be supported by a spacer or cross piece 38 secured beneath the platform. An intermediate connecting lever 39 is pivoted intermediate its ends on a pivot 40 disposed at the under side of the platform 10 and spaced therefrom by a cross piece 41 which may be relatively short as shown in Figure 2.

The forward end of the lever 39 is connected by a pivot 42 to the rear end of the front flexing lever 20, and at its rear end is connected by a pivot 43 to the forward end of the rear flexing lever 35. The main lever 39 has longitudinal slots 42' and 43' for the free play of their respective pivots 42 and 43 during the swinging of the levers, and the rear flexing lever 35 has an intermediate longitudinal slot 37' for the shifting of the lever 35 when swung. The forward flexing lever 20 has at its forward end a longitudinal slot 21' to prevent binding between the lever 20 and the bumper bar 17 and the other parts connected thereto.

This intermediate lever 39 acts to transmit motion of the forward flexing lever 20 in one direction to the rear flexing lever 35 in the opposite direction so that the runners 19 are flexed throughout their entire lengths uniformly and evenly with the curvatures substantially concentric and continuously in one direction. As the arms 15 at the forward end of the platform 10 are curved inwardly, ample space is provided within the marginal sides of the sled for the reception of the hands and feet in grasping the ends of the handle bar, and the handle bar is located rearwardly of the bumper or front bar 17 so that the hands and feet are protected against contact with objects encountered during travel of the sled. The outer extremities of the handles 26 may be provided with rope receiving openings 44 adapted to be used for either drawing the sled and guiding it, or for controlling the steering of the sled when the rider is standing thereon or is disposed in such position upon the sled as not to be able to grasp the handles by the hands or to engage the feet with the handles.

From the above description it will be noted that it is important to flex or curve the runners from end to end and uniformly in continuous arcs so that all parts of the runners will follow or track in a true curved path. This will offset or prevent any frictional drag of the runners against the supporting surface and can only be obtained where the flexing is equal and constant throughout the entire lengths of the runners.

What is claimed is:—

1. A flexible coasting sled, comprising a body portion, a pair of flexible runners mounted beneath the body portion, front and rear flexing levers connected to the front and rear portions of the runners, a connecting lever pivoted on the body portion and connected to said front and rear flexing levers for actuating the same in opposite directions, and operating means for swinging said levers to flex the runners.

2. A flexible coasting sled, comprising a body

- portion, a pair of runners disposed beneath the body portion, movable connecting means between the body portion and the runners to admit of the flexing of the runners beneath the body portion, 5
- 5 a front flexing lever connected to the forward ends of the runners, a rear flexing lever connected to the runners intermediate their ends, an intermediate lever connecting said forward and rear flexing levers, and a handle bar extending across the forward portion of the platform and connected to one of said levers for movement therewith to swing the levers when pressure is exerted on the handle bar to move the same.
- 10 15 3. A flexible coasting sled, comprising a sled body, a pair of runners, brackets spaced along said runners, movable connections between the brackets and the sled body for admitting flexing of the runners beneath the sled body, a bolster secured in fixed position across the intermediate portion of the sled body, a cross bar between an intermediate pair of said brackets for interconnecting the same beneath the sled body and slidably mounted on said bolster, a system of levers disposed between the forward ends of the runners and said cross bar and operable thereon in opposite directions, and operating means connected to the system of levers for swinging the same to flex the runners at spaced points in their 20 25 30 lengths.
4. A flexible coasting sled, comprising a sled body, a pair of runners for the sled body, pairs of brackets carried by the runners, means for pivotally and movably connecting the brackets to the sled body, a cross bar interconnecting the forward ends of the runners, a second cross bar interconnecting the runners near their rear ends, a system of levers disposed between the cross bars for moving the same relatively in opposite 35 40 45 directions, and means for swinging said levers to move said cross bar and flex the runners at spaced points in opposite directions.
5. A flexible coasting sled, comprising a sled body, runners mounted for flexing beneath the body, a bumper bar interconnecting the forward ends of the runners, a pair of inwardly arched arms disposed between the forward ends of the runners and the sled body, a handle bar extending across said inwardly arched arms at the forward end of the sled body, and a lever pivoted at one end to the bumper bar and fixedly pivoted at an intermediate point to the sled body adjacent the handle bar, said handle bar fixed upon said lever to move as a unit therewith for swinging the lever on its pivot when the handle bar is moved.
6. A flexible coasting sled comprising a sled body, a pair of laterally flexible runners mounted beneath the sled body, said runners having grooved lower edge portions providing spaced apart cutting edges for contact with the icy surface to stabilize the runners, a cross member interconnecting the forward ends of the runners and movable independently of the sled body, a second cross member interconnecting the intermediate portions of the runners, and a steering mechanism connected to said cross pieces for moving the same transversely in opposite directions for flexing the runners simultaneously in substantially concentric and continuous arcs. 5 10 15
7. A flexible coasting sled comprising a sled body, a pair of flexible runners mounted beneath the sled body, cross members interconnecting spaced portions of the runners, a lever for each cross member pivotally connected at one end thereto and pivoted intermediately on the sled body, a reversing lever pivotally mounted on the sled body and interconnecting the opposite ends of said first levers, and a handle bar fixed across one of said levers for operation to swing the same and swing all of the levers to flex the runners. 20 25 30 35
8. A flexible coasting sled, comprising a platform, a pair of runners, pivotal connections spaced apart lengthwise of the runners between the latter and the platform for supporting the runners beneath the platform, a handle bar mounted across the platform, and runner flexing means connected to the handle bar and to the runners at points spaced lengthwise thereof from said pivotal connections and operable in opposite directions for laterally shifting the runners at 35 40 45 50 55 said points out of their normal straight line positions and turning said pivotal connections to arch the runners throughout their lengths when the handle bar is operated.
9. A flexible coasting sled comprising a sled body, a pair of brackets disposed adjacent the rear end of the body, a second pair of brackets disposed forwardly thereof, a pair of runners secured to the respectively adjacent brackets extending forwardly of the second brackets and having laterally movable front ends, a cross bar connecting said second brackets and slidably transversely of the body, and means operable to positively move the cross bar in one direction and the front ends of the runners in the opposite direction including a handle bar and means extending from the cross bar, interconnected with the handle bar and pivoted to the body between the cross bar and the front end of the sled. 40 45 50 55
